UNITED STATES PATENT OFFICE

WILLIAM S. GATRELL, OF LEES SUMMIT, MISSOURI

WELL-DRILLING EQUIPMENT

Application filed April 20, 1926. Serial No. 103,191.

My invention relates to equipment to be employed in well drilling where high gas pressure is encountered. The invention contemplates equipping the upper end of the well in such manner that the drill stem may be introduced into and removed from the well even under extreme conditions of gas pressure.

In drilling wells with the rotary system of drilling in localities where gas pressure is common, it is always a problem to drill the well without danger of the well blowing in, in such manner as to wreck the well drilling equipment and ruin the well. Blow-out preventers and other similar devices have been devised for eliminating the hazards due to drilling under pressure. All the present equipment, however, is either inadequate or unsatisfactory because it does not allow the manipulating of the drill equipment when the apparatus is used.

It is an object of my invention to equip the well in such manner that the drilling may proceed and the pipe be handled in the well without danger of blow-out. It is a particular object of the invention to allow the removal of the drill stem from the well under high pressure and to control the flow of gas and liquid from the well when the stratum of high pressure is encountered.

It is desired to equip the upper end of the well casing so as to provide means for holding the pipe against upward movement and to also provide means whereby the drilling pipe may be allowed to move upwardly under restraint so as to gradually disconnect the sections of the pipe and allow its complete removal.

My device includes the employment of hydraulic means to restrain the movement of the pipe and of pipe engaging slips so arranged and mounted as to hold the pipe stationary at any desired position in the well.

The further details of construction by means of which my invention is carried out will be understood from a more detailed description which follows. Referring to the drawing herewith wherein a preferred embodiment of the invention is disclosed, Figs. 1, 2 and 3 illustrate the upper, intermediate

and lower sections, respectively, of my well equipment for carrying out the invention, some parts being shown in central vertical section and others in side elevation. Fig. 4 is a view partly in section of the upper end 55 of the casing frame, said view being taken at right angles to the view shown in Fig. 1. Figs. 5, 6 and 7 are transverse sections on the planes 5—5, 6—6 and 7—7, respectively, of Fig. 1. Like numerals are employed to 60 designate like parts in all the views.

In considering the equipment of a well wherein my invention may be employed, reference is made to Fig. 8 wherein the upper surface surrounding the well casing is cemented over, as shown at 1 in the drawing, and in doing so the surface casing indicated at 2 is cemented in position. It is to be understood that the said surface casing is of large diameter and extends downwardly into 70 the well for a comparatively short distance. Within the surface casing is another concentric pipe 3 which I shall term the outer casing, in that it is an outer pipe of large diameter extending downwardly for a material 75 distance into the well. The space between the surface casing and the outer casing is preferably shut off at the upper end by means of a stuffing box, indicated at 4.

The upper end of the casing 3 is equipped 80 with a head 5, ordinarily called a braden head. This head has a threaded connection with the upper end of the casing 3, its upper end being provided with a radial flange 6 which is provided with openings therein to 85 receive the clamping bolts 7 connected through the flange 8 of the gland 9 which forms part of a stuffing box, by means of which a sliding, fluid-tight connection is made between the casing 3 and the inner 90 casing 10.

The inner casing 10 extends to the lower end of the hole and projects upwardly through the braden head 5 for a short distance, as shown in Fig. 2. It has at its upper 95 end a large gate valve 11, ordinarily called the drilling valve. It is ordinarily open to allow the drill stem 12 to work through the housing of the valve. When the drill stem is withdrawn, however, the valve may be 100

closed to entirely shut off the upper end of the casing. The drilling valve is anchored to the braden head flange 6 by means of rods 15' connected within lateral lugs upon the lower end of the valve, as shown in Figs. 2 and 3.

Above the drilling valve is a swedged nipple 13 which is enlarged in diameter at its upper end and threaded for connection with a casing head 14 of special construction. Said casing head is preferably anchored to the concrete base 1 by means of anchor rods 15 extending through slotted lugs 16 on the lower end of the casing head and connected at their lower ends to anchor bolts 17 fixed in the cement. This anchoring means prevents any tendency of the casing head to be blown off under excessive gas pressure. The casing head has, as is common, a lateral outlet 18 connected to the T 19 through which the fluid may be allowed to pass upwardly through the pipe 20 to the ditch when drilling is proceeding. The lower pipe 21 connected with the T 19 is to allow the outlet 25 of oil when the well is brought in. A valve 22 in the oil line and similar valve 23 in the mud line allows the regulation of the fluid passing through the pipes.

The casing head has a passage 24 to allow space for the drill when it is withdrawn. Above this passage is formed a threaded socket 25 to receive the lower end 26 of a specially constructed tool joint pin. Said joint is formed with a recess 27 adjacent the inner opening therethrough to provide a seat for compressible packing means 28. The upper end of the joint above the packing receives a gland 29 which may be forced downwardly on the packing to compress the same by means of bolts 30 threaded into the upper end of the tool joint and having an adjustable connection with the upper flange 31 upon the gland.

The tool joint forms a support for a frame made up of two side plates 32 which are arcuate in shape, as shown in Figs. 6 and 7. Said plates are clamped on opposite sides of the tool joint head and are secured in position by cap screws 33. At their upper ends the said plates are fitted within lateral recesses 35 of the spider 36. The said spider 36, as shown in Fig. 4, comprises a circular ring having a central downwardly tapered opening therein forming a seat 37 to receive a set of pipe engaging slips 38. Said slips are of ordinary construction and are three in number. They are secured loosely at their upper ends to a ring 39 by means of bolts 40 extending through said ring and engaging in the upper ends of the jaws. The openings through the ring are large enough to allow a play of the bolts 40 therein so as to allow adjustment of the jaws.

The jaws may be operated by means of a lever 41 pivoted at 42 at one side of the spider

and having forked arms straddling the upper end of the slips and having a block 43 on each arm engaging within a peripheral groove 44 in the outer face of the ring. This allows the ring to rotate between the two blocks 43 but allows the ring with the slips thereon to be raised through the manipulating of the handle 45 in an obvious manner.

I also provide a second spider 46, spaced slightly above the gland 31. Said spider is of a general circular shape except that it has two oppositely extending arms 47, each of which has a notch or recess 48 therein to receive the spool shaped nut 49. Said nuts have a threaded engagement with the two upright threaded rods 50 mounted at their lower ends upon the upper portion of the tool joint head 26. It will be noted that the spider may thus be adjusted vertically along the drill stem by the rotating of the nuts 49 upon the rods 50.

The spider 46 has a central upwardly tapered seat 51 therein to receive the pipe engaging slips 52 operated through connecting with a ring 53 and the lever 54, similar in all respects to the ring 39 and the lever 41, previously described in connection with the upper slips. The lower lever 54 is below the spider, however, and must be raised to throw the slips into a position within the spider so as to grip the pipe and prevent it from being moved upwardly. It is to be understood that when the gas pressure is heavy within the well it may be about sufficient to lift the drill stem and tend to throw it upwardly out of the wall. It gives a vibratory movement to the drill stem whereby it is moved upwardly and dropped and thus it may be gripped with both the upper and lower sets of slips, and in some cases both sets of slips become locked firmly to the pipe so that they may not be easily disengaged from the pipe by ordinary means. In my arrangement, if the lower set of slips is locked it may be released by moving the spider bodily upward away from the slips by screwing the nuts 49 upwardly on the threaded shafts 50. When the lower slips have been thus released, the pipe may be raised, releasing the upper slip, thus doing away with the necessity of hammering upon the slips and damaging the equipment in an attempt to release the slips from the pipe.

The equipment thus described allows the operator to prevent the movement of the pipe in either direction and particularly to prevent the pipe from being blown out of the hole by pressure. When it becomes necessary to remove the pipe, however, it is dangerous to release the lower slips 52 without restraining the upward movement of the drill stem. This is done through means of a hydraulically operated hook 55 which is adapted to engage within the upper end of the drill stem 12 and to receive the hook, and I equip the upper end of the drill stem with a threaded

pin 56 having a recess 57 in the upper end thereof within which the hook may engage.

The said hook 55 is formed upon the upper end of a rod or shaft 58 which forms a piston rod in a hydraulic ram. The lower end thereof has a piston 59 thereon operating within a cylinder 60. To receive the hydraulic equipment including the cylinder 60, just described, I sink a shallow hole adjacent the well which is to be drilled to provide housing for the ram. This shallow well has an outer casing 61 therein and within this casing is received the outer barrel 62 of the ram. The lower end of the barrel 62 is closed by means of a threaded plug 63 and the upper end is connected with a head 64 which has a central passage 65 therethrough to fit closely about the piston rod or shaft 58. A stuffing box 66 within the upper end of the head maintains a close and fluid tight closure for the upper end of the cylinder. Said cylinder is screwed at 67 within the lower end of the head in spaced relation from the outer barrel 62. The barrel 62 may or may not have a stuffing box 71 closing off the space between the barrel and the outer end of the casing 61. Pressure fluid, preferably oil or water, under pressure may be forced into the barrel 62 through a valve controlled pipe 68, or it may be forced into the upper end of the cylinder 60 through the pipe 69 connected with the side of the head 64 and having a passage 70 in said head connecting said pipe with the upper end of the cylinder. It is contemplated that the fluid may be forced into the apparatus or allowed to move outwardly therefrom under control of the valves by ordinary equipment, such as is usually employed with hydraulic pressure operated devices of this character.

In the use of my device when the well has been drilled when under high pressure, the drill stem may be removed from the well without danger by releasing the engagement of the slips 52 from the pipe and allowing the pipe to be forced upwardly by the gas pressure under restraint of the hook 55 and the piston 59. In such case, the pressure above the piston may be relieved gradually through the operation of the valve in pipe 69, thus permitting the drill stem to be moved up a sufficient distance to expose the next adjacent lower tool joint in the drill stem. As will be obvious, any joints in the drill stem must be made flush with the outer surface of the pipe, and I contemplate, therefore, the employment of flush tool joints in the drill stem. When the next lower tool joint is exposed above the upper spider 36, the slips 52 will be forced into their seat to grip the pipe firmly and prevent its movement upwardly. The upper slips will also be placed in position to prevent any tendency of the pipe to fall should the gas pressure be removed to any extent. The hydraulically op-

erated hook 55 will then be rotated slightly to bring it out of alignment with the upper end of the drill stem and will be allowed to drop toward the lower end of its stroke. The tool joint may then be unscrewed and the upper section thereof removed and the hook may again be engaged within the upper end of the drill stem and the hydraulic pressure operated to allow the pipe to be moved upwardly as in the previous case, and to permit of this the slips 52 will be manually released. It will be obvious that some supporting means may be provided for the operating handle 54 of the lower set of slips when the slips are in position to release the pipe. No such means are shown, however, for purposes of clearness, it being obvious that many expedients may be adopted.

The advantages of this construction lie in the fact that a blow-out of the well is guarded against in a very effective manner, which allows the use of a rotary drilling rig in completing the well. The drill stem may be gradually removed in the manner described and when the lower end of the drill stem has passed the drilling valve 11, said valve may be closed tightly and the production from the well may be allowed to pass the valve under control through the outlet pipe 21 to storage without danger. The further advantages of the construction will be obvious to those skilled in the art.

What I claim as new and desire to protect by Letters Patent is:

1. In a device of the character described including a well casing, a casing head thereon, and a drill stem in said casing; the combination of a frame above said casing head, a drilling gland about said drill stem in said frame, means including said gland to preserve a tight fit about said drill stem, means on said frame above said gland to hold said stem from movement upwardly, and separate means to restrain said drill stem from rapid upward movement.

2. In a device of the character described including a well casing, a casing head thereon, and a drill stem in said casing; the combination of a frame above said casing head, a drilling gland about said drill stem in said frame, means including said gland to preserve a tight fit about said drill stem, means on said frame above said gland to hold said stem from movement upwardly, and hydraulically operated means to restrain said drill stem from rapid upward movement.

3. In a device of the character described including a well casing, a casing head thereon, and a drill stem in said casing; the combination of a frame above said casing head, a stuffing box about said drill stem, and manually operated means to hold said stem from movement upwardly, and hydraulically operated means to restrain said drill stem from rapid upward movement.

4. In a device of the character described a well casing, a drill stem therein, means to maintain a fluid tight fit between said drill stem and casing, adjustable means to grip said pipe to prevent its upward movement, and auxiliary means to allow its movement upwardly with a restraining force independently of said adjustable means. 70
5. In a device of the character described a well casing, a drill stem therein, means to maintain a fluid tight fit between said drill stem and casing, adjustable means to grip said pipe to prevent its upward movement, and auxiliary means to allow its movement upwardly with a restraining force, comprising a hydraulically operated rod, and a hook thereon adapted to engage within the upper end of said drill stem. 75
6. In a device of the character described a well casing, a drill stem therein having flush joints therein, means to maintain a fluid tight fit between said drill stem and casing, adjustable means including pipe engaging slips to grip said pipe to prevent its upward movement, and auxiliary means to allow its movement upwardly with a restraining force. 80
7. In a device of the character described including a well casing, a casing head thereon, a frame on said head, a stuffing box in said frame about said drill stem, a spider mounted adjustably on said frame, upwardly tapered pipe engaging slips in said spider about said drill stem, means to adjustably support said drill stem, and means to move and support said slips. 85
8. In a device of the character described, a well casing, a drill pipe therein, means to preserve a fluid tight fit between said casing and drill pipe, and hydraulically operated means to restrain the upward movement of said drill pipe in said casing, and two sets of oppositely disposed slips whereby movement of the drill stem in either direction may be controlled. 90
9. In a device of the character described, a well casing, a drill pipe therein, means to preserve a fluid tight fit between said casing and drill pipe, a hydraulic cylinder adjacent said casing, a piston therein, a rod on said piston, and a hook on said rod engaging the upper end of said drill pipe. 100
10. In a device of the character described, a well casing, a drill pipe therein, means to preserve a fluid tight fit between said casing and drill pipe, a hydraulic cylinder adjacent said casing, a piston therein, a rod on said piston, and a hook on said rod engaging the upper end of said drill pipe, and detachable pipe engaging means on said casing below said hook to hold said pipe from movement upwardly. 110
11. In a device of the character described a casing head, a frame above said casing head and supported thereon, a pair of spiders on said frame, one of said spiders having an up- wardly tapered seat and the other having a downwardly tapered seat, tapered pipe-engaging slips in said seats, and means to move said slips to and from pipe-engaging position. 115
12. In a device of the character described a casing head, a frame above said casing head and supported thereon, a pair of spiders on said frame, one of said spiders having an upwardly tapered seat and the other having a downwardly tapered seat, tapered pipe-engaging slips in said seats, and means to move said slips to and from pipe-engaging position, said means comprising a ring connected at the larger ends of said slips, and a lever connected with said ring. 120
13. In a device of the character described a casing head, a frame above said casing head and supported thereon, a pair of spiders on said frame, one of said spiders having an upwardly tapered seat and the other having a downwardly tapered seat, tapered pipe-engaging slips in said seats, and means to move said slips to and from pipe-engaging position, the lower of said spiders being mounted to allow adjustment vertically relative to the frame. 125
14. In a well drilling equipment, a surface casing, an outer casing, a stuffing box adapted to seal the annular opening between said casings, an inner casing, a head on said outer casing and a fluid tight gland carried thereby, and adapted to seal the opening between said outer and inner casings, a drill stem in said inner casing, a nipple above said head, rods attached to said nipple and anchored to said surface casing, and means anchored to said nipple to restrain upward movement of the other said casings. 130
15. In a well drilling equipment comprising means to prevent blowouts, including a drill stem, two separately operable means to restrain upward movement of the drill stem due to internal well pressure, and another separate means to restrain downward movement of said drill stem upon lessening of the internal well pressure. 135
16. In a well drilling equipment comprising means to prevent blowouts, including a drill stem, two separately operable means to restrain upward movement of the drill stem due to internal well pressure, and another separate means to restrain downward movement of said drill stem upon lessening of the internal well pressure, one of the first said means being adjustable in a vertical position to prevent locking of the drill stem by the last said means. 140
17. In a well drilling equipment comprising means to prevent blowouts, including a drill stem, two separately operable means to restrain upward movement of the drill stem due to internal well pressure, and another separate means to restrain downward movement of said drill stem upon lessening of the internal well pressure. 145

internal well pressure, one of the first said means being adjustable in a vertical position to prevent locking of the drill stem by the last said means, the other of the first said means being adjustable to restrain the upward and to compel the downward movement of said drill stem.

18. In a device of the character described, a well casing head, a drill stem therein, means to seal the upper end of said casing head about said drill stem, rods mounted on said casing head, a spider adjustable vertically on said rods, and means in said spider arranged to grip said drill stem to restrain upward movement thereof.

15 In testimony whereof I hereunto affix my signature this 14th day of April, A. D. 1926.

WILLIAM S. GATTRELL.
